UNITED STATES PATENT OFFICE.

GEORGE W. MCCALLEN, OF WHEATLAND, PENNSYLVANIA.

OIL-BURNER.

1,082,130.

Specification of Letters Patent.

Patented Dec. 23, 1913.

Application filed November 10, 1910. Serial No. 591,684.

To all whom it may concern:

Be it known that I, GEORGE W. MCCALLEN, a citizen of the United States, residing at Wheatland, in the county of Mercer and 5 State of Pennsylvania, have invented certain new and useful Improvements in Oil-Burners, of which the following is a specification.

This invention relates to oil burners, and 10 in the adaptation shown, is primarily intended for use in producing a forge fire.

One of the objects of my invention is the provision of an oil burner in which heavy 15 low grade oil is used in connection with a fan blast.

A further object of my invention is the provision of internal baffle rings and the arrangement of the burner that will effect a thorough atomization of the oil in intermix- 20 ture with the air blast.

Further objects and purposes of my invention will appear from the drawing, the specification describing the same, and the claims appended thereto, in which is fully set forth 25 the arrangement of parts, combination of elements, and specific structural details, properly comprised within the scope of the same.

Figure 1 is a side cross sectional view of 30 the air flue and mixing chamber showing a cross sectional view of the burner proper and oil feed pipe. Fig. 2 is a cross sectional view of the flue and burner taken on the line A A of Fig. 1 and looking in the direction of the air flow.

Referring now to the two figures in which like reference characters designate like parts, (1) represents the air flue and mixing chamber which is cast integral with the flange 40 portion (2). The flue is adapted to be secured to the furnace wall by bolts passing through the apertures (3) in the flange (2) so that the short forwardly projecting end of the flue extends into the furnace. The 45 flue shown is L shaped with the unmixed air coming down the vertical leg. On this portion of the flue at (4) I provide a blast gate casting (5) in which the air blast issuing from (6) is regulated by the blast gate (7). 50 That portion of the flue projecting into the furnace is provided with an interior annular baffle (8), the purpose of which will be more fully set forth hereafter. Centrally of the diameter of the horizontal portion of the 55 flue and on the outer side of the elbow, I provide a port, cast with the flue and inte-

riorly threaded to receive the rear end of the oil feed pipe (10). Interposed between (10) and the oil feed pipe (12) is a suitable hand valve (11) by which the flow of oil into the burner is regulated. The forward end of the oil pipe (10) is provided with a choked nozzle (13) having an oil port (14) therein, and the exterior of this end of the pipe is threaded to receive the spider bar 60 (15). Suitably secured to the outer ends of the spider, preferably by bolts and nuts (18, 20) is the rear flange portion (17) of the mixing cone (19). The forward part of this cone is provided with an interior annular baffle (21), the interior face of the baffle ring being threaded as at (22).

In operation, the air coming down the vertical leg of the flue is driven by a fan, not shown, while the oil, under a four to ten 75 pound pressure, issues from the port (14). The rear diameter of the mixing cone is preferably about three-fourths of the interior diameter of the horizontal leg and thus takes in the greater part of the air current to catch up the oil. That portion of the air current within the mixing cone and farthest removed from the oil port is caught at the forward part of the cone by the annular baffle and thrown across the central 80 current of air and oil. The baffle ring being threaded, provides a rough surface against which the broken current of air and oil is now thrown, thus assisting in the intermix- 85 ture and allowing the mixed oil and air to 90 issue in a spray from the mixing cone. The atomized oil is now carried forward surrounded by an unmixed air current toward the front portion of the mixing chamber where the outer air soon strikes the annular baffle 95 (8) and is thrown across the main current thus giving a highly mixed current of air and atomized oil, the structure of which current, however, contains the heavy oil vapor in the interior of the current.

In practice, I have found it possible to produce a highly efficient atomization of the oil with merely a fan blast providing only a six ounce pressure where a burner and mixing chamber constructed in accordance with 105 the foregoing description is used. In the particular construction of my burner and arrangement of the flue and burner, I can produce a higher combustible intermixture of oil and air using only a fan blast and 110 low grade oil, than can be equaled by other burners using a high blast pressure as pro-

2

duced in blowers together with a high or medium grade oil. I have found in practice that this is accomplished by providing the interior annular baffles in the forward 5 part of the mixing cone and the forward part of the flue which serves as a mixing chamber, and also by roughening the interior of the baffle ring on the mixing cone which in the adaptation shown and described is 10 threaded.

I am aware of the prior art in burners using burners and mixing chambers with reduced and conical shaped nozzles, but in my burner I not only accomplish the results obtained 15 in these other burners, to wit, converging the outer air current toward the inner air current and affording an expansion of the mixture as it leaves the nozzle end, but in using an interior baffle ring having 20 its inner face abruptly angled against the air current, I produce a highly efficient breaking of the air and oil molecules and consequently more intimate intermixture of them.

25 I claim;

1. In an oil burner the combination of a mixing chamber, said mixing chamber having a mixing cone concentrically suspended therein, said mixing cone having a ring 30 interiorly located in the forward converging end of the cone, said ring presenting an abrupt angle to the air current passing through said cone, the inner surface of said ring being threaded to afford resistance to 35 the current passing through said ring, and means for supplying air to said cone and chamber and oil to said burner, substantially as shown and described.

2. In an oil burner the combination of a 40 tubular L shaped casting, comprising an air flue and a mixing chamber, an oil feed pipe

entering the outer side of the elbow and projecting centrally of the horizontal leg of the casting, a spider secured to the forward part of the oil feed pipe, a mixing cone secured 45 at its larger end to the spider surrounding the forward end of the oil feed pipe, a baffle ring, located interiorly of the forward part of the mixing cone, having its inner surface roughened, and means for supplying 50 air to the flue, substantially as shown and described.

3. In an oil burner, the combination of a tubular L shaped casting having a mixing cone suspended centrally of the interior of 55 the horizontal leg, a baffle ring, having its inner surface roughened, located interiorly of the forward part of the mixing cone, and an interiorly located annular baffle at the forward part of the horizontal leg of the 60 casting, substantially as shown and described.

4. In an oil burner, the combination of a tubular casting having a mixing cone centrally suspended therein, a baffle ring, having 65 its inner surface roughened, located interiorly of the forward part of the cone, means for supplying air at the rear of said casting, so that part of the air entirely surrounds the mixing cone and part enters its 70 rear, and means for supplying oil at the central rear part of the cone, whereby an air current is thrown across the line of oil ring, substantially as shown and described. 75

In testimony whereof I have affixed my signature in presence of two witnesses.

GEORGE W. McCALLEN.
